UNITED STATES PATENT OFFICE.

HORATIO G. GILLMOR, OF WASHINGTON, DISTRICT OF COLUMBIA.

RAIL-ANCHOR.

1,317,364.

Specification of Letters Patent. Patented Sept. 30, 1919.

Application filed May 27, 1916. Serial No. 100,380.

To all whom it may concern:

Be it known that I, HORATIO G. GILLMOR, a citizen of the United States, residing at Washington, in the District of Columbia, 5 have invented new and useful Improvements in Rail-Anchors, of which the following is a specification, accompanied by drawings.

My invention relates to devices known as rail anchors, rail stays or anticreepers and 10 one of its objects is to form a simple device which will prevent the longitudinal movement of the rails of railways.

A further object of the invention is to provide a pressure producing part which, while 15 of ample strength to withstand all the stresses to which it is subjected, will have such a degree of elasticity or resiliency as will insure the tightness of the grip of the device under all conditions.

20 A further object of the invention is to provide a device which shall grip both sides of the rail base and both the edges thereof in a manner to firmly hold the rail against creeping movement.

25 A further object of the invention is to provide a device which shall have an efficient grip upon the rail under all conditions and which cannot be loosened or detached from the rail by a reverse movement 30 of the rail, vibration, changes in temperature or other accidental causes.

One embodiment of the invention is shown in the accompanying drawing, in which:—

Figures 1, 2 and 3 are, respectively, a 35 plan view, a side elevation and an end view, showing the rail in section, of the device in operative position on the rail, a portion of which and of one of the ties upon which it is supported are shown. Fig. 4 illustrates 40 one of the positions assumed by the parts when being applied to the rail and is an end view, showing the rail in section and one of the parts partly in section. Fig. 5 is a side elevation showing a part of the rail in 45 section and one of the parts of the device in the position in which it is before the second of the parts is placed. Fig. 6 is a larger view of the spring or pressure producing clamp by which the parts are secured.

50 Similar letters refer to similar parts throughout the several views.

In the embodiment of the invention illustrated in the drawings A represents a rail having a base flange B of the usual type resting 55 upon and supported by the tie C which

is embedded in the ballast material and is a fixed part of the road-bed, while D is a transverse member engaging the base flange B and E is a spring or pressure producing part which engages the base flange B of the rail 60 A at one side of and above the rail base B and the transverse member D below the rail A. The member D is constructed with an arm or jaw F and a longer arm or jaw G arranged to engage the upper surfaces of the 65 rail base B at opposite sides of the rail and the member D is so constructed as to permit it to be placed in position on the rail base B by placing the arm G and the portion H of the member in engagement with one edge 70 of the rail base B, raising the other end of the member D until the arm F can, by transverse movement of the member D, be brought into full engagement with the upper surface of the base flange B of the rail. The 75 member D is provided with a rail base edge engaging shoulder or abutment I arranged to engage the edge of the rail base B at one side of the rail and another shoulder or abutment K arranged to engage the other 80 edge of the rail base B. The shoulder or abutment K is beveled as at J, and the upper surface of the body portion of the transverse member D is warped; so that, with this member D in position upon the rail base 85 B, before the other member, the part E, is placed and forced into position, the upper face of the transverse member D will stand away from the bottom of the rail at L (Figs. 4 and 5); so that the shoulder K will, in 90 the normal unstressed condition of the member D, be somewhat below the rail bottom. Upon the lower portion of the member D at the end at which are the abutment K and the arm G and between the arm G and 95 the abutment K there is formed the bearing surface M at each side of which are small shoulders N. The transverse member D is constructed with a tie abutment O and the arms F and G are stiffened by webs P and Q and the abutments or shoulders I and K are stiffened by webs or flanges R and S. The spring pressure producing part E is preferably made of rectangular steel curved at T so as to form surface U corresponding to 100 the bearing surface M on the transverse member D and is also curved at V and provided with a long arm W.

The device is applied to the rail by placing the member D with the arm G and the 110

portion H engaging the upper surface and edge of the rail base at one side, after which, by turning the member D through a small angle, the arm F may be brought clear of the rail edge at the other side of the rail. Movement of the member D transverse to the rail will then bring it to the position illustrated in Figs. 4 and 5 with the arms F and G in engagement with the upper surfaces of the rail base B at opposite sides of the rail and the abutment I engaging one edge and the abutment K about to engage the other edge of the rail base B. The spring pressure producing member E is then placed with the surface U engaging the bearing surface M of the member D and moved angularly about this bearing until the arm W engages the upper corner of the rail base B as illustrated in Fig. 4. From the position shown in this figure the spring E may be forced to the final operative position shown in Figs. 1, 2 and 3 either by driving the spring E or preferably by the use of a suitable wrench and the first effect of the forced angular movement of the part D is to cause the arm F to press down upon the upper surface of the base B of the rail and to press the upper portion of the body of the member D, adjacent the abutment I, upwardly against the bottom of the rail base B. As the part E is forced farther the arm G is pressed downwardly upon the upper surface of the rail base B and the stress brought upon the body portion of the member D draws the warped upper surface of the body portion of the member D up against the rail bottom and forces the abutment K into engagement with the edge of the rail base B, the beveled portion J of the abutment K insures proper engagement of the abutment with the rail base edge and tends to cause the rail to be gripped between the two abutments I and K. The warping of the upper surface of the body of the member D distributes the pressure of this warped surface, when drawn up into contact with the rail bottom, and causes the member D to bear upon the rail base B over the whole bottom with an upward pressure the amount of which will depend upon the elastic strength of the material of which the member D is constructed.

The form of the spring pressure producing part E gives this part great resiliency, both the curve V and the curve T contributing to this, and with the part E made of resilient steel the form of this part will permit it to spring and temporarily change shape while being forced into position and to exert a strong pressure upon the rail and the member D. This and the form of the member D give the device as a whole great elasticity combined with the strength necessary to effectually grip and hold the rail against tendencies to move forward (the

direction referred to as forward is indicated by the arrow in Fig. 2).

Should the rail for any reason move in the reverse or backward direction it will readily be seen that, even if the tie abutment O 70 should be held in the ballast, in any way, the part E will hold the device securely locked upon the rail so that it cannot be loosened and for any forward movement of the rail the engagement of the abutment O 75 with the tie will, with the device in operative position upon the rail, hold the rail against such movement. Generally the grip of the parts upon the rail base when they are in their final operative position will be 80 sufficient to hold the rail securely against all tendency to creep, but should this not be the case and slight movement of the rail in relation to the member D occur it will be at once automatically checked by the slight angular 85 movement of the part D which is held at the bottom by the shoulders N, adjacent the bearing M on the member D, while the arm W will be carried forward by the rail base as the rail moves forward. Any tendency 90 of the rail to creep is thus self checked.

While I have described the invention as embodied in a preferred construction modifications might be made without departing from the principles of the invention. Therefore I do not wish to be understood as limiting the invention to the particular construction, arrangement and devices shown and described except so far as these limitations are specifically set forth in certain of the 100 claims herein.

I claim and desire to secure by Letters Patent:

1. A rail anchor comprising two rail gripping elements, one of which is provided with means for engaging a fixed portion of the road bed in opposition to the tendency of the rail to creep and one of which comprises a spring element which engages the rail base above and the other element below the rail 110 base at one side of the rail.

2. A rail anchor comprising two rail gripping elements, one of which is formed with means for engaging a fixed portion of the road bed in opposition to the tendency of the rail to creep, and has rail bottom engaging surfaces which are normally warped, and one of which comprises an element bearing upon the top of the rail base and engaging the other element to draw and hold the 120 warped surfaces into contact with the rail bottom.

3. An anticreeper comprising two rail gripping elements, one of which is formed with a tie-abutting flange, and one of which 125 comprises a spring which engages, at one side of the rail, the upper surface of the rail base and the lower part of the end of the other element and presses the same up against the rail bottom.

4. A rail stay comprising two rail gripping elements, one of which is formed with means for giving the device a fixed position in the road bed as against the tendency of the rail to creep, and one of which comprises a spring member which embraces one edge of the rail base and one end of the other member and clamps the rail between them.
- 10 5. A pressure producing part for anti-creepers comprising a spring constructed from a rolled bar arranged to embrace one side of the rail base and one end of a rail bottom engaging element and to exert pressure thereon.
- 15 6. A rail anchor comprising two rail gripping pieces, one of which consists of an element embracing both sides of the base of the rail, and one of which comprises a pressure producing member which embraces one side of the rail base and said element and exerts pressure thereon, one of said elements being provided with a tie engaging flange.
- 20 7. A device for preventing the creeping of rails comprising two rail gripping members, one of which is formed to engage a fixed portion of the road bed in opposition to the tendency of the rail to creep, one of which comprises a normally warped transverse element engaging the rail base at opposite sides of the rail, and the other a clamp engaging the rail base above and said element below the rail and pressing said warped transverse element up against the
- 30 rail bottom.
- 35 8. A rail anchor comprising two rail engaging and gripping elements, one of which is formed with a tie-abutting flange, one of which consists of a member embracing both sides of the rail base, and the other being adapted to engage said member and to be forced into engagement with the rail base by angular movement about an axis below and between the edges of the rail base.
- 40 45 9. An anticreeper comprising two rail engaging and gripping parts, one consisting of a part embracing the base of the rail and the other being elastic and adapted to engage said part below the rail and the rail base above the rail bottom.
- 50 55 10. A device for preventing the creeping of rails comprising a spring adapted to embrace one side of the rail base, a part adapted to engage the rail base at the other side of the rail and intervene between the rail bottom and said spring, said part having a transverse portion which is initially twisted and means for engaging a tie.
- 60 11. A rail anchor comprising a transverse element engaging the rail base at one side of the rail, a spring which engages said element below and the base of the rail above the bottom of the rail at the other side of the rail and tie engaging means attached to one
- 65 of said elements.
12. An anticreeper comprising a normally warped transverse part engaging the rail base at one side of the rail and a spring engaging the upper surface of the rail base and said element at the other side of the rail and pressing said element up against the rail bottom, one of said elements being provided with a tie engaging portion.
13. A pressure producing part for rail anchors constructed from a rolled bar having one end bent to form an arm adapted to engage the upper surface of the rail base and the other end bent to form a portion adapted to rotatably engage the rail base engaging element below the rail.
14. A rail stay comprising a resilient clamp engaging the upper side of the rail base at one side of the rail and an elastic transverse member which intervenes between said clamp and the rail bottom and embraces the other side of the rail base and is provided with means for engaging a fixed portion of the road-bed in opposition to the tendency of the rail to creep.
15. A rail anchor comprising a rail base embracing part formed with a tie-abutting flange and a spring member adapted to engage said part below and to be forced into engagement with the rail base above the rail bottom by rotation of said spring about said part.
16. A rail stay comprising a resilient transverse part constructed to embrace the rail base flange and provided with a tie abutment and a pressure producing member adapted to embrace the rail base and said transverse part at one side of the rail so as to put said resilient transverse part under tension.
17. An anticreeper comprising a rail embracing part formed with a tie abutting flange and a spring clamp adapted to engage said part below and the rail base above the rail bottom at one side of the rail and to be forced into position by transverse angular movement of said spring clamp about said part transverse to the rail.
18. A rail anchor comprising a transverse element adapted to engage the rail bottom at one end and one side of said element and to stand normally out of contact with the rail bottom at the other end and the other side of said element, a pressure producing element adapted to engage said transverse element and the upper surface of the rail base and draw said transverse element up into contact with the rail bottom and means adapted to engage a stationary portion of the road bed.
19. An anticreeper comprising a part formed at one end with an arm adapted to fit the upper surface of the base flange at one side of the rail, at the other end with a longer arm extending around the opposite side of the rail base and with a tie-engaging
- 125
- 130
- 135

flange and a spring adapted to engage said part and the upper surface of the rail base at one side of the rail.

20. A rail anchor comprising a part arranged for transverse application below the rail base having at one end an arm arranged to engage the upper surface of the rail base and an abutment adapted to engage the vertical edge of the rail base at one side of the rail, an arm at the other end of said part extending around and engaging the upper surface of the other side of the rail base and a tie-engaging flange intermediate of the two arms and a spring adapted to engage said part and the upper surface of the rail base at one side of the rail.

21. A rail stay comprising a transverse element having arms at the ends thereof adapted to engage the upper surfaces of the rail base at opposite sides of the rail and abutments adapted to engage opposite vertical edges of the rail base and a tie abutment between the ends of said element and a spring adapted to engage said element and the upper surface of the rail base at one side of the rail.

22. An anticreeper comprising a rail embracing part which engages upper surfaces of the rail base at opposite sides of the rail and is provided with a tie abutting portion and a pressure producing part adapted to engage said part below and the rail base above the rail bottom and to be forced into position by transverse angular movement about said part.

23. A rail anchor comprising a transverse part adapted to engage the rail bottom at one end and one side of said part and to stand normally out of contact with the rail bottom at the other end and the other side of said part and provided with a tie abutment, and a pressure producing element adapted to engage said transverse part and the upper surface of the rail base at one side of the rail and draw said transverse part up into contact with the rail bottom.

24. In a rail anchor, the combination of a member adapted to engage one side of a rail base, extend transversely under the rail in contact with the bottom of the rail base along one edge and, in normal condition, out of contact with the bottom of the rail base along the other edge of said member, means engaging the upper surface of the rail base and said member operative to raise one corner of said member, whereby said member is subjected to a torsional strain and caused to exert upward pressure upon the bottom and downward pressure upon the top of the rail base, and means adapted to engage a stationary portion of the road bed.

25. A rail anchor comprising two rail gripping elements one of which has arms

engaging the upper surfaces of the rail base at opposite sides of the rail and is provided with means for engaging a fixed part of the road-bed in opposition to the tendency of the rail to creep, and one comprising a clamp which engages the other element below and the rail base above the rail bottom and causes the arms of said other element to press down upon and the body of said element to press upward upon the rail base.

26. An anticreeper comprising rail gripping elements, one of which has a tie abutment and portions engaging the upper surface of the rail base at opposite sides of the rail, and one of which is a spring which bears against the upper surface of the rail base and the other element and clamps the rail between said spring and said other element.

27. A rail anchor comprising an elastic transverse member which is normally twisted and a clamp embracing one end of said member and one side of the rail base so as to put said member under stress and draw the twisted transverse portion up into contact with the rail bottom, one of said parts being provided with a tie-abutting member.

28. An anticreeper comprising a warped transverse part having arms engaging the opposite surfaces of the upper side of the rail base and a tie-engaging flange, and a spring embracing one end of said part and one side of the rail base so as to put said warped part under stress and clamp the rail base between said part and said spring.

29. A rail anchor comprising a transverse piece having a warped surface adapted to be forced into contact with the flat surface of the bottom of the rail and two arms adapted to engage the upper surfaces of the rail base at opposite sides of the rail and a clamp constructed so to engage the rail base and said transverse piece that rotation of said clamp transverse to the rail will put said piece under stress and draw the warped surface up into contact with the rail bottom.

30. An anticreeper comprising a warped transverse element having arms and abutments adapted to engage the upper surfaces of the rail base and the vertical edges of the rail base at opposite sides of the rail and a spring which embraces one end of said element and one side of the rail base so as to put said element under stress, one of said elements being formed with a tie-abutting member.

31. In an anticreeping device for rails, the combination of a warped rail engaging and gripping element constructed to engage the top and bottom of the base flange of the rail and a rail engaging device constructed to engage said element for drawing the warped surface thereof into contact with the rail base.

32. A device for preventing the creeping of rails, comprising a rail embracing and clamping element arranged to engage the base flange at one side of the rail and to extend transversely beneath the rail with a downward twist and a part constructed to engage said element and the upper surface of the rail base at the other side thereof for effecting the gripping action of the device and means adapted to engage a stationary portion of the road bed.
33. In an anticreeping device for rails, a tie engaging rail gripping element having a downward twist away from the rail base arranged for transverse disposition beneath the rail and a rail engaging device pivotally engaging said element for drawing the downwardly twisted element into contact with the rail bottom.
34. In a rail anchor, the combination of a resilient bar adapted to engage one edge of a rail and to extend under the rail base with a downward twist away from the rail base a part engaging the upper surface of the other edge of the rail base and said bar for securing said bar to the rail so as to put the bar under a torsional strain, and means adapted to engage a stationary portion of the road bed.
35. In a rail anchor, the combination of a resilient bar provided with an integrally formed jaw for engaging one edge of the rail base and adapted to extend under said rail base with a downward twist and a clamp engaging the other side of the rail base and said bar for securing said bar to the rail so as to put the bar under torsional strain.
36. In a rail anchor, the combination of two rail clamping elements, one of which comprises a member extending under the base of the rail transversely thereof with one edge in contact with the bottom of the rail base and having a downward inclination away from the bottom of the rail base toward the other edge of said member and one side of the rail, and means for effecting an operative engagement between said elements and the rail which subjects said member to a torsional strain upwardly toward the bottom of the rail base one of said elements being provided with means for engaging a tie in opposition to the tendency of the rail to creep.
37. An anticreeper comprising a member which clamps one side of the rail base and has a portion which extends under the rail transversely thereof and is normally warped downwardly away from the bottom of the rail base, a clamping element which clamps the other side of the rail base between said element and said member and causes the warped portion of said member to be strained and exert upward pressure which is distributed across the bottom of the rail base and means for engaging a fixed portion of the road bed.
38. A device for preventing the creeping of rails, comprising two rail gripping elements, one of which is formed with means for engaging a fixed portion of the roadbed in opposition to the tendency of the rail to creep and is provided with arms adapted to engage the upper surfaces of the rail base and abutments adapted to engage the opposite edges of the rail base, and one of which comprises an element bearing upon the rail base above and the other element below the rail bottom.
39. A rail anchor, comprising a warped transverse part having arms engaging the upper surfaces of the rail base and abutments engaging the opposite edges of the rail base, an element embracing one end of the said part and one side of the rail base so as to put said warped part under strain and clamp the rail base between said part and said element and means adapted to engage a stationary portion of the road bed.

H. G. GILLMOR.
